UNITED STATES PATENT OFFICE.

WALTER S. EARLEY AND ROBERT W. KILPATRICK, OF PHILADELPHIA, PENNSYLVANIA, ASSIGNEES, BY MESNE ASSIGNMENTS, TO THE EARLEY DRY GRAPHITE LUBRICATOR COMPANY, OF PHILADELPHIA, PENNSYLVANIA, A CORPORATION OF PENNSYLVANIA.

LUBRICATING DEVICE.

1,109,742.

Specification of Letters Patent.

Patented Sept. 8, 1914.

Application filed May 21, 1913. Serial No. 768,930.

To all whom it may concern:

Be it known that we, WALTER S. EARLEY and ROBERT W. KILPATRICK, citizens of the United States, residing in the city and county of Philadelphia and State of Pennsylvania, have invented certain new and useful Improvements in Lubricating Devices, of which the following is a specification.

10 The object of our invention is to provide a novel, simple and efficient device by means of which flake graphite may be regularly and uniformly fed to a cylinder or its equivalent, in which various degrees of steam, air 15 or other pressures are produced, for the purpose of lubricating the cylinder and the devices associated therewith for the production of the different pressures, the device being periodically actuated by the regularly recurring changes of pressure in the cylinder to regularly and automatically feed a uniform quantity of graphite to the cylinder.

Our invention includes a casing for containing the graphite and having a passage-way communicating with the cylinder and a valve for controlling the passage of graphite from the casing to the cylinder and our invention, particularly, includes a novel construction and arrangement of a valve head 30 adapted to be forced by the pressure within the casing toward a seat which surrounds the said passageway and thereby instantly and effectually prevents any graphite from leaving the casing after the pressure therein falls below the pressure within the cylinder, all as will be hereinafter fully described and particularly claimed.

In the accompanying drawings, illustrating our invention, Figure 1, is a vertical section through our improved lubricating device and a portion of an engine cylinder to which the lubricating device is operatively connected. Fig. 2, is a horizontal section through the lubricating device, on line 2—2 of Fig. 1.

Referring to the drawings, 3 designates our improved lubricating device, 4 a portion of an engine cylinder to which the device 3 is connected and 5 a portion of the piston 50 which is reciprocated within the cylinder 4 during the operation of the engine, as is common and well known. During this well known operation of the engine, steam is regularly admitted to and exhausted from

the respective ends of the cylinder in prescribed order, thereby causing the pressure to rise and fall within the cylinder; and, as the construction and operation of the valves and other devices which are concerned in causing the rise and fall of the pressure are common and well known, no description or illustration thereof is deemed necessary herein.

Our lubricating device 3 is constructed and connected as follows: 6 designates a hollow casting forming a casing inclosing a chamber 7 for the graphite. The top of the casting 6 has an opening 8 therein, and screwed into the opening 8 is a suitable head 9 which normally closes the opening 8, steam tight, and which may be removed when desired to permit the supply of graphite to the casing 6 through the opening 8. Screwed into the bottom of the casting 6 is a stem 10, a steam tight joint being formed between the stem and the casting 6. The bottom of the stem 10 is screwed on to the upper end of a short pipe 11, the lower end of which is screwed into the cylinder 4. The pipe 11 affords communication between the cylinder 4 and a vertical passageway 12 formed in a plug 13 which is screwed into the lower end of a vertical opening 14 in the stem 10. The opening 14 extends through the upper portion of the stem 10 which projects up into the chamber 7, as shown. The top of the plug 13 forms a valve seat 15 which surrounds the passageway 12; and seated on the top of the plug 13 is the lower end of a vertically-movable, cylindrical valve head 16 which is slidably fitted to the opening 14 and rests normally on the valve seat 15 and closes communication between the upper portion of the opening 14 and passageway 12.

Screwed into the upper end of the opening 14 is a screw 17 which is vertically adjustable therein and which is provided with a lock nut 18 adapted to engage the top of the stem 10 and lock the screw in different positions of adjustment. The bottom of the screw 17 forms a stop for the valve head 16 and limits the extent of the upward movement thereof. By adjusting the screw 17 the range of movement of the valve head 16 may be nicely regulated. The screw 17 has a vertical tapered passageway 21 extending therethrough, smaller at its lower

end than at its upper end and for a purpose hereinafter explained.

The opening 14 in the stem 10 communicates with the chamber 7 by two lateral passageways 19 and 20 which extend through the wall of the stem 10, one above the other, and above the valve seat 15, as shown. When the valve head 16 is raised, communication between the passageway 12 and chamber 7 is established through the opening 14 and one or both of the passageways 19 and 20, in accordance with the position of the screw 17 which limits the movement of the valve head 16.

15 The operation of the device is as follows: As the steam or other pressure enters the cylinder 4 and is exhausted therefrom to cause the pressure within the cylinder to rise and fall at regular intervals, in the usual manner, the valve head 16 is raised and lowered with the rise and fall of pressure within the cylinder 4. As the pressure within the cylinder 4 raises, it lifts the valve head 16 into contact with the bottom of the screw 17 and enters the chamber 7 through the passageway 12, the opening 14 and one or both of the passageways 19 and 20, in accordance with the position of the screw 17. As the pressure within the cylinder 4 falls below the pressure within the chamber 7, part of the steam within the chamber 7 returns to the cylinder 4 and carries therewith a quantity of the graphite contained within the chamber 7, until the pressure within the chamber 7 forces the valve head 16 back to its seat 15 and stops the further discharge of graphite to the cylinder. The pressure within the chamber 7 holds the valve head 16 against the seat 15 until the pressure within the cylinder 4 again exceeds the pressure within the chamber 7, when the operation just described is repeated. It will thus be understood that each time the pressure within the cylinder 4 rises and falls a small quantity of the graphite contained within the chamber 7 will be discharged into the cylinder 4 for the purpose of lubricating the same and the parts associated therewith.

50 The provision of the passageway 21 permits the pressure within the chamber 7 to act upon the top of the valve head 16 to quickly return it to its seat 15, although it is not essential that the passageway 21 be present, as, in its absence, the pressure within the chamber 7 will find its way through the passageways 19 and 20 and around the valve head 16 to the top thereof and return it to and hold it against its seat.

60 It will be readily understood that by adjusting the screw 17 the quantity of graphite fed to the cylinder 4 each time the valve head is raised and lowered may be

around the passageway 12 leading to the cylinder 4, and the valve head 16 being held against the seat by the pressure within the chamber 7 is one of the essential features of our invention, as by it we are enabled to control, accurately, the amount of graphite fed to the cylinder, each time the valve head is operated. This accurate feeding of the graphite is, as is well known, a very important consideration in proper lubrication. 75

We claim:

1. The combination with a fluid pressure cylinder, of a casing adapted to contain a lubricant, a hollow stem extending into the casing, a vertically - movable cylindrical valve head loosely fitted within said stem and guided thereby, said stem having a part forming a valve seat upon which the bottom of said valve head rests, said stem having a passageway surrounded by said seat and leading therefrom to the interior of the cylinder and normally closed by said valve head, said stem having a lateral passageway therein above said seat and opening into the casing, said lateral passageway affording communication between the first named passageway and the interior of the casing when said valve head is raised above the lateral passageway, and means for limiting the upward movement of the valve head. 95

2. The combination with a fluid pressure cylinder, of a casing adapted to contain a lubricant, a hollow stem extending into the casing, a vertically - movable cylindrical valve head loosely fitted within said stem and guided thereby, said stem having a part forming a valve seat upon which the bottom of said valve head rests, said stem having a passageway surrounded by said seat and leading therefrom to the interior of the cylinder and normally closed by said valve head, said stem having a lateral passageway therein above said seat and opening into the casing, said lateral passageway affording communication between the first named passageway and the interior of the casing when said valve head is raised above the lateral passageway, and an adjustable screw screwed into the top of said stem and adapted to limit the upward movement of the valve head. 105

3. The combination with a fluid pressure cylinder, of a casing adapted to contain a lubricant, a hollow stem extending into the casing and communicating with the cylinder, said stem having a lateral passageway therein opening into the casing, a vertically-movable, cylindrical valve head within said stem and normally closing said passageway, said passageway affording communication between the interior of the casing and the interior of the cylinder when the valve head is raised above the passageway, and a part limiting the upward movement of the valve head and provided with a passageway com- 120 125 130

municating with the interior of the casing and closed by the upper end of the valve head when it is in the uppermost position.

4. The combination with a fluid pressure cylinder, of a casing adapted to contain a lubricant, a hollow stem extending into the casing, a vertically - movable cylindrical valve head within said stem, said stem having a part forming a valve seat upon which the bottom of said valve head rests, said stem having a passageway surrounded by said seat and leading therefrom to the interior of the cylinder and normally closed by said valve head, said stem having a lateral passageway therein above said seat and opening into the casing, said lateral passageway affording communication between the first named passageway and the interior of the casing when said valve head is raised above the lateral passageway, and a part limiting the upward movement of the valve head, and provided with a passageway communicating with the interior of the casing and closed by the upper end of the valve head when it is in the uppermost position.

5. The combination with a fluid pressure cylinder, of a casing adapted to contain a lubricant, a hollow stem extending into the casing, a vertically - movable cylindrical

valve head within said stem, said stem having a part forming a valve seat upon which the bottom of said valve head rests, said stem having a passageway surrounded by said seat and leading therefrom to the interior of the cylinder and normally closed by said valve head, said stem having a lateral passageway therein above said seat and opening into the casing, said lateral passageway affording communication between the first named passageway and the interior of the casing when said valve head is raised above the lateral passageway, and an adjustable screw screwed into the top of said stem and adapted to limit the upward movement of the valve head, said screw having a passageway extending therethrough and communicating with the interior of the casing and closed by the upper end of the valve head when it is in the uppermost position.

In testimony whereof we affix our signatures in the presence of two witnesses.
